UNITED STATES PATENT OFFICE.

PIERRE KOLGRAF, OF BRUSSELS, BELGIUM.

METALLIC SLEEPER FOR RAILROADS.

SPECIFICATION forming part of Letters Patent No. 404,043, dated May 28, 1889.

Application filed November 22, 1888. Serial No. 291,538. (No model.) Patented in Belgium December 5, 1885, No. 71,102; in France January 5, 1886, No. 173,396; in England March 16, 1886, No. 3,699, and in Italy July 12, 1886, No. 20,243.

To all whom it may concern:

Be it known that I, PIERRE KOLGRAF, a citizen of Germany, residing at Brussels, in Belgium, have invented certain new and useful Improvements in Metallic Sleepers for Railroads, (which have been patented in Belgium December 5, 1885, No. 71,102; in France January 5, 1886, No. 173,396; in England March 16, 1886, No. 3,699, and in Italy July 12, 1886, No. 20,243;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the accompanying drawings, Figure 1 is a cross-section of the metallic tie, showing one of the rail-chairs and part of a rail in side elevation. Fig. 2 is a longitudinal vertical elevation of the tie and chairs, the rails being shown in cross-section, illustrating the arrangement thereof in a paved roadway. Fig. 3 is a top plan view of a tie and chairs with the rails keyed thereto. Fig. 4 is an enlarged longitudinal elevation of a portion of the tie and of a rail-chair, the rail, as well as the groove-rail, being shown in cross-section. Fig. 5 is a plan view of Fig. 4. Fig. 6 is a like view showing a slight modification in the construction of the rail-chair. Fig. 7 is a longitudinal vertical elevation of a tie and its rail-chairs, the rails being shown in cross-section. Fig. 8 is a plan view of Fig. 7. Fig. 9 is also an enlarged plan view showing a further modification in the construction of the rail-chair. Fig. 10 is a longitudinal elevation showing the arrangement of the tie and its chairs as applied to a macadamized or asphalt road-bed, and Fig. 11 is a top plan view of a tie and its rail-chairs of the construction shown in Figs. 9 and 10.

The object of this invention is to provide a metallic tie of simple construction and of greater strength than the ordinary **U** or **T** sleepers or ties heretofore proposed for rail-ways.

The invention consists, essentially, in the construction of the tie and in the combination

therewith of a rail-chair, substantially as hereinafter described, and as set forth in the claims, the essential feature of the invention lying in the cross-sectional form of the tie, and in combination therewith of a chair for the rails, acting as a brace for the tie.

Referring to the drawings, T indicates the tie, that is composed of two sections or bars of iron or steel having the form or substantially the form of a letter, **Z**, in cross-section—that is to say, the sections are formed of a web, t^2 , from the upper and lower ends of which project flanges t and t' in reverse directions, the flange t serving as a bed or bearing plate, while the flange t' serves as a bedding-plate, to be embedded in the ballast of a track or the paving material of a roadway. The two bars or girders are or may be connected together by means of bolts simply, and the rails may be secured thereto in any desired manner, the connection being so arranged as to hold the two bars at a proper distance from each other to form a good bearing for the rails on the upper flange, t' .

In practice I prefer to provide a separate bearing or chair, C, for the rails, which also serves to connect the two sections of the tie firmly together.

In Figs. 1 to 3 I have shown this chair as constructed with open lateral sides c , open top c' , and open bottom c^2 , the solid front and rear walls, c^5 , being connected by a transverse web, c^3 , Fig. 1, and with inwardly-projecting lugs or horns c^4 , for the foot of the rails, which seat upon the upper edge of the front and rear walls, c^5 . The chair C is bolted to and between the tie-sections by means of bolts t^3 , as shown, thus providing not only a proper support for the rail R, but also a very strong connection for the two sections of the tie T. Where the tie is employed in an ordinary ballasted or a macadamized road-bed and it is desired that the tread of the rails should be flush with said road-bed, I employ an auxiliary rail, R', Figs. 2 and 4, that is bent outwardly, as shown at r' , the web r^2 of such rail bearing against the web of the main rail R and resting upon the foot r of such rail, as more plainly shown in Fig. 4. This rail R' may be bolted to the rail R, if desired; but it

has been found in practice that the usual connection—such as the fish-plate connection of two sections of main and auxiliary rails—is sufficient to securely hold the auxiliary rail sections in position, said rails being further supported by the ballast or other paving material of the road-bed in which they are embedded.

In road-beds constructed of concrete the auxiliary rail may be dispensed with, as shown in Fig. 10, a gutter being formed along the inside of the rails R for the flange of the car-wheels to run in. The chair shown in Figs. 4 and 5 has a vertical transverse web, c^6 , as shown in dotted lines in said Fig. 4. In Figs. 6 to 8 the lateral sides of the chair are somewhat modified in construction, said sides having an opening formed in them, instead of being entirely open, and the projecting lugs or horns being made broader to provide a greater locking-surface, while the chair shown in Figs. 9 to 11 has its four sides solid and its top and bottom open, the front and rear walls being connected or braced by a vertical trans-

verse web, c^6 .

The rails R may be secured to the chairs C in any convenient manner—as, for instance, by means of a split key, K, as shown.

By means of the described construction the ties T may be so embedded in the roadway or track as to leave the rails or the tread of the rails above the same; or the said ties may be so embedded in the roadway or track as to leave the tread of the rails R flush therewith,

thus doing away with the objectionable feature of projections above the road-bed. 35

The construction of the tie is also such as to offer a greater resistance to pressure or strain either vertically or laterally than the ordinary T or U ties, and also provides greater 40 bearing-surfaces, as will be readily seen at a glance of Fig. 1.

Having described my invention, what I claim is—

1. A metallic railway-tie, T, consisting of 45 two bars composed of a vertical web, and flanges t^t , projecting at right angles thereto in opposite directions, and a chair, C, interposed between said bars and bolted to the vertical web thereof, said chair being provided 50 with lugs or horns c^4 for the reception of the rail-foot, substantially as and for the purposes specified.

2. A metallic railway-tie, T, consisting of 55 two bars composed of a vertical web, and flanges t^t , projecting at right angles thereto in opposite directions, and a chair, C, interposed between said bars and bolted to the web thereof, said chair having open sides and top, a web, c^3 , connecting the front and rear 60 walls, and lugs or horns c^4 , for the rail-foot, substantially as and for the purposes specified.

In testimony whereof I affix my signature in presence of two witnesses.

PIERRE KOLGRAF.
